STAMP APPLYING MACHINE

Fred Gehring, San Francisco, Calif.

Application June 28, 1949, Serial No. 101,697

1 Claim. (Cl. 216—25)

1

The present invention relates to improvements in a stamp-applying machine, and has particular reference to a machine adapted for applying postage stamps to envelopes and the like. It consists of the combinations, constructions, and arrangement of parts, as hereinafter described and claimed.

It is proposed in this invention to provide a stamp-applying machine that is compact in construction, easily loaded with a roll of postage stamps, and upon being operated will apply one stamp at a time to an envelope or the like.

Broadly speaking, I provide a machine of the character described having an envelope-receiving slot and a stamp-discharge chute leading to an envelope inserted into the slot. A single push knob is utilized for delivering water from a reservoir to the portion of the envelope upon which the stamp is to be applied, feeding the stamp into proper position relative to the envelope, severing the stamp from the roll, advancing the severed stamp from the roll, and pressing the severed stamp into final position on the envelope. A number of stamps may be applied to the envelope in succession by consecutive operations of the push knob.

Another object of the invention is to provide a machine that will feed the stamps positively to the envelope at a speed which will preclude the stamps from being torn accidentally during the feeding thereof. More specifically, each stamp is injected initially one-half way into the discharge chute during the return movement of the push knob from a previous operation. During the depression of the push knob for any particular operation, the water is sprayed onto the underlying envelope, and thereafter the stamp is fully inserted into the delivery chute, where it is severed and applied to the envelope.

Other objects and advantages will appear as the specification continues. The novel features will be set forth in the claim hereunto annexed.

For a better understanding of the invention, reference should be had to the accompanying drawings, forming part of this application, in which:

Figure 1 is a vertical longitudinal section taken through my stamp-applying machine, and illustrating a roll of stamps in which the adhesive is applied to the outer or exposed surface of the roll, the parts being shown at the start of a stamp-applying operation;

Figure 1a discloses a slight modification of delivering the stamps when the adhesive is disposed on the inner surfaces of the stamps in the roll;

2

Figure 2 is a top plan view of the machine, with parts broken away to show the interior construction;

Figure 3 is a view similar to Figure 1, illustrating the parts at the completion of a stamp-applying operation;

Figure 4 is an enlarged view of a portion of Figure 1; and

Figure 5 discloses a stamp applied to an envelope by my machine.

While I have shown only the preferred form of my invention, it should be understood that various changes, or modifications, may be made within the scope of the appended claim without departing from the spirit thereof.

Detailed description

In carrying my invention into practice, I provide a housing indicated generally at A, which is supported on a base B so as to leave an envelope-receiving slot 10 therebetween at the forward end of the housing, as shown in Figures 1 and 3. These views disclose an envelope C inserted into the slot 10, with a portion of the envelope positioned beneath an open-ended stamp-discharging chute 11. The latter leads to and communicates with the envelope-receiving slot.

A roll of stamps designated at D is mounted in the housing. These stamps are delivered one at a time to the chute 11 by means hereinafter described. After each stamp is inserted into the chute, it is severed from the remaining stamps in the roll by a presser foot 12. The latter is disposed for reciprocation in the chute 11 and is operated by a push knob 14.

Prior to each severed stamp being applied to the envelope C by the foot 12, a small quantity of water 15 from a reservoir E is injected by a pump mechanism F upon the surface of the envelope against which the stamp is applied. This pump, also, is actuated by the push knob 14 in timed relation with the feeding and severing of the stamps. The reservoir is filled through an opening provided when a plug 15' is removed.

Returning now to the roll of stamps D, it will be noted the stamps are arranged in end-to-end relation to form a strip D1. This strip is wound on a spool 16, which is rotatably supported on a shaft 17. The latter is anchored to the side wall 18 of the housing A by any suitable means, for example a cap screw 19 (see Figure 2).

The strip D1 of stamps is guided over the top of an idler roller G, and then is trained along a lower peripheral section of a combined feed and ratchet roller H so as to enter the chute

11 through a slot 20 fashioned in the rear wall of the latter.

The stamps are provided by the Post Office Department with longitudinal rows of perforations 21 fashioned along the opposite marginal sections of the strips (see Figures 2 and 5). Moreover, transverse perforations 22 are arranged between adjacent stamps. The leading stamp D2 in the strip D1 is severed from the next stamp along the transverse perforations 22 by the presser foot 11 when the latter is depressed.

As illustrated in Figures 1 to 3, inclusive, radial pins 23 project from the periphery of the roller H at spaced-apart points therealong corresponding to the height of each stamp. These pins engage with the transverse perforations 22 and move the stamps toward the chute 11 with positive action. Circumferential grooves 24 are provided in the idler roller G to receive the ends of the pins 23 that extend through the stamps.

Moreover, a stamp-guiding plate 25 is disposed beneath the roller H and holds the stamps up against the periphery of that roller. Also, this plate has recesses 26 therein to receive the projecting ends of the pins 23 as the roller H is turned. As the stamps approach the chute 11, they are guided beneath a plate 27 (see Figures 1 and 3).

It will be noted that the rollers G and H are supported for rotation on shafts 28 and 29, respectively. These shafts are secured to the side wall 18 of the housing A by cap screws 30 and 31, respectively, or by other suitable fastening means (see Figure 2).

For the purpose of precluding the roll of stamps D from loosening, I make use of a weight-ed arm 32 having a rounded end 33 bearing against the outer surface of the roll. This arm is swingably mounted on a pivot pin 34, which is anchored to the side walls of the housing A. A coil spring 35 (see Figure 1) is disposed to pull the rounded end of the arm against the roll of stamps with sufficient force to require the feed roller H to exert a slight pull on the strip D1 of stamps in advancing the latter to the chute 11.

The side wall 36 of the housing A has a section 36a that may be removed for giving access to the roll of stamps D, the idler roller G and the swingable arm 32. This will permit a new roll of stamps to be inserted over the shaft 17 and the strip D1 of stamps to be trained over the idler roller G and underneath the feed roller H. Cap screws 37 and 38 are threaded into the shafts 17 and 28 for holding the section 36a in place.

In Figure 1, the adhesive surface 39 of the stamp strip is disposed outermost. Accordingly, when the strip D1 is guided over the idler roller G and pulled downwardly over the lower periphery of the feed roller H, the adhesive surface will be on the underneath side of the stamps. However, in Figure 1a the adhesive surface 40 of the stamps is arranged on that side of the stamps facing toward the center of the roll D3. In this instance, it is necessary to unroll the stamps in a counter-clockwise direction and to guide them beneath an idler roller 41 before training them over the roller G.

Next, I shall describe the pump F for discharging a small quantity of the water 15 onto the portion of the envelope C against which the stamp is to be applied. In Figures 1 to 4, I show an upright cylinder 42 disposed alongside the chute 11. A piston 43 is arranged for reciprocation in this pump cylinder and has a rod 44 70 75

secured thereto and rising therefrom through guide brackets 45. A coil spring 46 is interposed between the uppermost of these brackets and a pin 47 anchored to the upper end of the rod 44 (see Figure 4). This rod is urged upwardly by the spring 46 into a normal position just above an orifice 48 provided between the cylinder 42 and the reservoir E.

Referring to Figure 1, it will be observed that a bell-crank lever 49 is swingably mounted on a pin 50. One arm of this lever bears against the top of the piston rod 44, while its other arm is provided with a roller 51. When this bell-crank is swung in a counter-clockwise direction, it will depress the rod 44 against the action of the spring 46 until the piston 43 covers the orifice 48 (see Figure 3). At this time, flow of water 15 from the reservoir E to the cylinder 42 is cut off.

In Figures 1 and 3, I disclose a reciprocable shank 52 secured to the presser foot 12 and to the push knob 14. This shank has a laterally-projecting cam 53 thereon having an inclined lower end 53a arranged to bear against the roller 51. The shank 52 is urged upwardly into the position illustrated in Figure 1 by a coil spring 54. The latter may be disposed within a thimble 55 secured by a pin 56 to the push knob 14 and to the shank 52. This thimble is slotted at 57 so as to slide over a spider 58 against which the lower end of the spring 54 bears.

As soon as pressure is released on the push knob 14, the shank 52 will be returned to its normal upper position (Figure 1) by the spring 54. This will retract the cam 53 and the spring 46 will raise the piston 43 again.

A second piston 59 is disposed in the cylinder 42 below the piston 43. Piston 59 is urged upwardly into the position shown in Figure 4 by a spring 60 surrounding a stem 61 depending from the piston 59. This stem may be guided in an apertured cap 62 screwed into the bottom of the cylinder 42 and has a head 61a thereon to limit upward movement of the piston 59. The purpose of this second piston is to control the discharge of a small body of water 15a (see Figure 4) through one or more outlet orifices 63 leading from the cylinder 42 to the chute 11.

These outlet orifices may be inclined downwardly toward the envelope C, as suggested in Figure 4, and also fanned laterally, as shown in Figure 2. This will direct a minute spray of water over the portion of the envelope upon which the stamp is to be applied. It will be noted that the body of water 15a is trapped between the coacting pistons in Figure 4. The lower piston 59 seals the orifices 63 (see Figures 1 and 4) until such time as this piston is forced downwardly against the action of the spring 61 by the downward movement of the piston 43.

In other words, the piston 43 moves downwardly, closing the inlet orifice 48; then further downward movement of the piston 43 will cause the lower piston 59 to descend until the outlet orifices 63 are uncovered by the lower piston. At this moment, the water will be sprayed over the portion of the envelope C disposed below the chute 11.

The combined feed and ratchet roller H, previously mentioned, is fashioned with a plurality of teeth 64 spaced around its circumference. The peripheral spacing between adjacent ratchet teeth is equal to one-half of the height of each stamp D. On the other hand, the spacing of the pins 23 around the periphery of the roller H is equal to the height of each stamp. The rear-

son for these different spacings will be apparent as the specification continues.

When the machine is first loaded with the stamps, the leading stamp D2 is projected one-half of its height into the chute 11 (see Figures 1 and 4). A pawl 65 is hinged at 66 to the upper end of a rockable lever 67. This lever is mounted intermediate of its ends on a journal pin 68 and carries a roller 69 at its lower end. A spring 70 is connected to the pawl 65 to pull the pawl toward the ratchet and also urge the lever 67 to swing in a clockwise direction.

Turning now to Figure 1, this view discloses the shank 52 in its uppermost position. A crescent-shaped cam 71 is fixed to the shank diametrically opposite the cam 53. Figure 1 illustrates the cam 71 arranged immediately above the roller 69. As the shank 52 is depressed, the cam 71 will contact with the roller 69 and swing the pawl 65 and lever 67 into the dot-dash line position shown in this view. This movement will retract the free end of the pawl from the notch 64a of one ratchet tooth and bring the pawl into engagement with the next notch 64b of the following ratchet tooth.

As the shank 52 continues to descend, the cam 71 will be moved into a position below the roller 69, as in Figure 3. Prior to the presser foot 12 reaching its lowermost position, the cam 71 will allow the lever 67 to swing in a clockwise direction. At this time, the spring 70 will move the pawl 65 to the right, thus turning the feed roller H a distance equal to one-half of the height of the stamp. Accordingly, the entire stamp D2 will be projected into the chute 11. By this time, the pump F has discharged its water spray onto the upper surface of the envelope C.

Further downward movement of the presser foot 12 will sever the leading stamp D2 from the strip of stamps, and the stamp D2 will be pressed into intimate contact with the envelope and become glued thereto.

When the operator releases the push knob 14, the shank 52 will be moved upwardly by the spring 54. On its up-stroke, the cam 71 will retract the pawl 65 again into the dot-dash line position shown in Figure 1. As the shank approaches the upper limit of its travel, the cam 71 will free the roller 69 and the pawl 65 will be pulled to the right by the spring 70. This will turn the feed roller H in a clockwise direction and will advance another stamp one-half way into the chute 11.

Now the machine is ready for the next cycle. Each complete downward movement of the push-knob 14 will apply another stamp to the envelope, while each upward movement of the shank 52 will project a stamp one-half way into the chute 11. This manner of delivering the stamps will reduce the speed at which the stamps must be advanced, thus reducing the likelihood of tearing the stamps.

The base B may be provided with a guide plate 72 at its forward end. This plate includes a downwardly-inclined section 72a over which the envelope C may slide during insertion of the envelope into the slot 10. Moreover, rubber pads 73, or the like, are provided underneath the base B to space the latter above a supporting surface 74 to prevent the surface from being marred.

It is quite obvious that my stamp-applying machine may be made in various sizes to accommodate rolls of stamps of different lengths and denominations, for office and family use, etc.

The arrangement of the roller 51 and cam 53

on the diametrically-opposed side of the shank 52 from that occupied by the roller 69 and cam 71 will serve to reduce strain on the shank. Also, the spring 54 operates axially of the shank.

Summary of operation

The operation of my stamp-applying machine is summarized as follows:

In the event that a roll of stamps D is being used having its adhesive surface 39 disposed outwardly, the roll is arranged on the shaft 17 in the manner shown in Figure 1. On the other hand, in the event that a roll of stamps D3 is being utilized, in which case the adhesive surface 40 faces towards the center of the roll, the strip of stamps is guided beneath the idler roller 41 as in Figure 1a. In either event, the strip D1 of stamps is guided over the top of idler roller G with the adhesive surface towards this roller.

The strip is extended beneath the combined feed and ratchet roller H, and the leading stamp D2 projected one-half of its height into the discharge chute 11, as shown in Figures 1 and 4. The radial pins 23 on the feed roller are introduced through transverse perforations 22 provided between adjacent stamps (see Figure 2).

At this time, the push knob 14 occupies its uppermost position, as disclosed in Figure 1. Now an envelope C is introduced into the slot 10, with a portion of the envelope underlying the stamp-discharge chute 11. Next, the operator depresses the knob 14 to force the shank 52 downwardly.

During the initial downward movement of the shank 52, the lower inclined end 53a of the cam 53 will become active on the roller 51, swinging the bell-crank lever 49 in a counter-clockwise direction. This will depress the rod 44 and its piston 43 into the position shown in Figure 3, that is, the piston 43 will cover the reservoir-pump cylinder orifice 48. The small body of water 15a trapped between the pistons 43 and 59 will force the latter downwardly against the action of the spring 60 until the pump cylinder-chute orifice or orifices 63 are uncovered. At this time, water will be sprayed over the portion of the envelope disposed under the chute 11 upon which the stamp is to be applied.

As the shank 52 moves downwardly, the cam 71 and roller 69 will swing the lever 67 in a counter-clockwise direction, as illustrated by the dot-dash line position in Figure 1. This will retract the pawl 65 from the ratchet notch 64a to the ratchet notch 64b. As soon as the cam 71 passes below the roller 69, the spring 70 will swing the pawl 65 to the right, advancing the feed roller H a distance equal to one-half the height of a stamp. Thus the stamp will be projected completely into the chute 11. This has occurred after water has been sprayed onto the envelope. Further downward movement of the shank 52 will cause the presser foot 12 to sever the stamp now disposed in the chute from the strip D1 of stamps. The severed stamp will be forced into intimate contact with the envelope.

When the operator releases pressure on the knob 14, the shank 52 and its cams 53 and 71 will be forced upwardly by the coil spring 54 until they occupy the full line positions shown in Figure 1. The return movement of the shank and cam 71 will cause the pawl 65 to turn the feed roller H in a clockwise direction to such an extent as to advance another stamp one-half of its height into the chute 11. At the same time, the pump mechanism F will be reset to the start-

ing position disclosed in Figure 1. The machine is ready now for a repeat operation.

I claim:

In a stamp-applying machine: a stamp-delivering chute; a reciprocable shank having a presser foot disposed in the chute; a rotatably mounted feed roller having ratchet teeth fashioned around the periphery thereof; a pawl assembly pivotally mounted on the machine and engaging with the ratchet teeth; said pawl being spring biased to urge the rotation of the feed roller a predetermined distance to feed a stamp for a distance of one-half its height; a cam fixed to the reciprocable shank and adapted to contact one end of the pawl assembly upon both upward and downward movement of the shank whereby the pawl assembly will be retracted by the cam to the succeeding ratchet tooth for each down and up movement of the reciprocal shank

and allow the rotation of the roller due to the biasing force after the cam has passed the pawl assembly for each down and up movement; whereby the stamp is advanced one-half its height on the down movement of the shank and advanced the other half of its height on the up movement of the shank.
